BRAKE-SPRING REMOVAL TOOL

Paul Romaniuk, 5258 Calhoun St., Dearborn, Mich.

Filed Jan. 24, 1966, Ser. No. 758

Term of patent 14 years

(Cl. D54—13)

FIG. 1 is a perspective view of a brake-spring removal tool showing my new design. The broken lines illustrating the brake shoe and spring assembly are shown for illustrative purposes only;

FIG. 2 is an enlarged end elevation of the tool;
FIG. 3 is a fragmentary side view of the terminal end;
FIG. 4 is a top plan view thereof; and

FIG. 5 is a fragmentary perspective view thereof.

The dominant features of my design resides in the portions shown in full lines.

I claim:

The ornamental design for a brake-spring removal tool, as shown and described.
